BABY BOTTLE PROTECTOR AND HEAT RETAINER

Filed March 20, 1929

INVENTOR.
Matthew J. Cole
BY *Colton H. Blackley*
ATTORNEY

UNITED STATES PATENT OFFICE

MATTHEW J. COLE, OF BROOKLYN, NEW YORK

BABY-BOTTLE PROTECTOR AND HEAT RETAINER

Application filed March 20, 1929. Serial No. 348,452.

This invention relates generally to protectors and has more particular reference to a novel baby bottle protector and heat retainer.

The invention has for an object the provision of a device of the class mentioned, which is of simple durable construction, desirable in use and efficient in action, and which can be manufactured and sold at a reasonable cost.

10 The invention proposes the use of a rubber container provided with a flannel lining and made of a top and bottom section separable for permitting the insertion of a baby bottle. A nipple may be engaged upon the 15 top end of the top section which is reduced for receiving the nipple. A means may be provided for normally holding the top and bottom sections in engaged positions. Window apertures are formed in the container 20 for permitting an inspection of the contents thereof.

For further comprehension of the invention, and of the objects and advantages thereof, reference will be had to the following description and accompanying drawings, and to the appended claims in which the various novel features of the invention are more particularly set forth.

In the accompanying drawing, forming a 30 material part of this disclosure:—

Fig. 1 is a side elevational view of a device constructed according to this invention.

Fig. 2 is a vertical sectional view thereof.

Fig. 3 is a horizontal sectional view thereof.

35 Fig. 4 is a view similar to Fig. 1, but disclosing a modification thereof.

Fig. 5 is a fragmentary vertical sectional view, taken on the line 5—5 of Fig. 4.

Fig. 6 is a fragmentary vertical sectional view, taken on the line 6—6 of Fig. 4.

Fig. 7 is a fragmentary vertical sectional view, taken on the line 7—7 of Fig. 6.

Fig. 8 is a similar view to Fig. 7 showing a modified form of joining my bottle protector.

45 The reference numeral 10 indicates generally a rubber container having a top section 11 and a bottom section 12. The top end of the top section has a reduced neck 13 with flange sections 14 for receiving a nipple 15.

50 The lower end of the top section has a re-

duced portion 16 for engaging within an increased opening 17 in the top of the lower section 12. The arrangement is such that the sections may snugly fit together and frictionally maintain their engaged positions.

55 Each of the sections are provided with a flannel lining 18 or any other suitable padding material for engaging against the sides of a baby bottle and aiding in maintaining the heat thereof. A plurality of fall absorbing projections 19 project from each of the sections of the container for striking the ground and absorbing the shock in the event that the container and contained bottle is dropped.

60 A plurality of window apertures 20 are formed in a vertical row in the container, both the top and lower sections for permitting an inspection of the contents thereof. The inner flannel lining 18 necessarily must have 65 similar apertures aligned with the apertures 20 for permitting the said inspection. Preferably several of the projections 19 should be arranged on the lower end of the container 70 for acting as legs in supporting the container in a vertical position.

75 In the modified form of the device illustrated in Figs. 4, 5 and 6 the top section is shown with a projecting pin 21 near its lower edge engaging in a bayonet slot 22 formed in the bottom section at its top edge. A nipple lever 23 is pivotally mounted intermediate of its ends as at 24 on the outer side of the container and has an inner end 25 projecting into the wall forming the container. The co-axial

80 spring 26 normally tends to urge the outer end of the lever 23 outwards. A flexible stiff wire 26^a connects at its top end with the inner end 25 and passes thru an opening 27 in the side of the container to the very bottom thereof. In the closed condition of the container with the pin 21 completely within the bayonet slot 22 an aperture 28 aligns with the opening 27 so that when a nipple is engaged upon the top of the container, the nipple lever 23 will be moved inwards for moving the wire 26^a downwards into the aperture 28 and locking the sections of the container against rotation so that the pin 21 cannot be withdrawn from the bayonet slot.

As shown in Fig. 7 the top section 16 is provided with a plurality of male members 16^a of the snap fasteners adapted to engage a plurality of corresponding female members 17^a secured to reduced portions 17 of the top section 11. In Fig. 8 the reduced portion 16' is made to interlock with a reduced portion 17' of the top section 11.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A baby bottle protector and heat retainer, comprising a container of rubber with a flannel lining, and consisting of an upper and a lower section joined for separating upon relative rotation, the top of the upper section being reduced for receiving a nipple, a lever 20 pivotally mounted on said reduced portion and arranged for depression upon the engagement of a nipple and upon depression moving a wire for latching the sections 25 against rotation.
2. A baby bottle protector and heat retainer, comprising a container of rubber with a flannel lining, and consisting of an upper and a lower section joined for separating upon relative rotation, the top of the upper 30 section being reduced for receiving a nipple, a lever pivotally mounted on said reduced portion and arranged for depression upon the engagement of a nipple and upon depression moving a wire for latching the sections 35 against rotation, said wire passing thru a longitudinal aperture in the side of the container upper section and upon said motion engaging in an aperture in the container lower section.

45 In testimony whereof I have affixed my signature.

MATTHEW J. COLE.
